APPARATUS FOR DRILLING BORE HOLES

Filed Jan. 9, 1945

UNITED STATES PATENT OFFICE

2,507,122

APPARATUS FOR DRILLING BOREHOLES

Louie F. Smith, South Houston, Tex., assignor of one-half to A. F. Clark and one-half to C. J. McWhorter, both of Harris County, Tex.

Application January 9, 1945, Serial No. 571,987

2 Claims. (Cl. 255—24)

1

This invention relates to an apparatus for drilling bore holes.

An object of the invention is to provide apparatus of the character described for drilling bore holes in the earth formation and which embodies a tubular drilling string, or stem, having a drill secured on the lower end thereof with a sample recovery tube leading from the drill upwardly through the stem to the ground surface and spaced inwardly from the drill stem thus providing a channel between the stem and tube through which the drilling fluid may be forced downwardly to the drill, said drill being provided with outlet ports from said channel to the formation at the bottom of the bore; and said apparatus being provided with means for controlling the return flow of the drilling fluid either upwardly through the bore outside of the drill stem or upwardly through the sample recovery tube to wash away the drill cuttings and to return samples of the formation through the tube to the ground surface for inspection.

In drilling ordinary formation where samples are not desired the drilling fluid may be returned back up through the bore around the drill stem and carried off to the slush pit but when it is desired to recover and inspect samples of the strata being drilled the construction is such that the drilling fluid may be returned up through the sample recovery tube so as to carry the samples up through said tube where they may be recovered and inspected.

The apparatus has been primarily designed for drilling, and recovering samples of, hard formation although it may be used for ordinary drilling purposes.

The invention also embodies a novel method for controlling the return flow of the drilling fluid so as to carry off the drill cuttings or so as to enable the operator to recover samples of the formation for inspection when desired.

With the above and other objects in view the invention has particular relation to certain novel features of construction, operation and arrangement of parts and to a novel method, examples of which are given in this specification and illustrated in the accompanying drawings, wherein—

Figure 1 shows a side elevation, partly in section, of the drilling apparatus as in operation; and

Figure 2 shows a cross, sectional view taken on the line 2—2 of Figure 1.

Referring now more particularly to the drawings wherein like numerals of reference designate similar parts in each of the figures, the nu-

2

meral 1 designates a tubular drill stem. This stem is made up of a plurality of sections which may be connected by coarse threads such as 2 so that the sections may be quickly connected and disconnected.

Attached to the lower end of the stem there is a drill 3. A diamond core drill is shown in the illustration. At its lower end this drill is reduced in its internal diameter forming the inside, annular, upwardly facing shoulder 4. The lower end of the drill is also provided with one or more outlet ducts 5 through which drilling fluid may reach the bottom of the bore.

Supported on the shoulder 4 and extending upwardly through the drill stem there is a sample recovery tube 6 which is spaced inwardly from the drill stem thus providing a channel 7 for the downward flow of the drilling fluid. The duct 5 is connected into this channel.

20 The numeral 8 designates the well casing which is set in the well bore and which is spaced outwardly from the drill stem to provide a return channel 9 for the drilling fluid.

The tube 6 is held centered relative to the drill 25 stem by means of suitable spacers 10, and is composed of sections.

A casing head 11 is secured to the upper end of the casing 8 and surrounds the drill stem. A seal is provided between the upper end of the casing 30 head and the drill stem. Any selected type of seal may be used, an ordinary stuffing box 12 being shown.

The casing head has a flow line 13 connected into it beneath the seal and this flow line is 35 equipped with a conventional type of shutoff valve 14.

The flow line may lead to the ordinary pit which is usually provided to receive the returning drilling fluid.

40 Connected to the upper end of the drill stem 1, by means of coarse threads 15, there is a swivel designated generally by the numeral 16. This swivel comprises a tubular rotatable swivel body 17, surrounding which is the stationary jacket 18 which is provided with an inlet 19 through which the drilling fluid is forced by a suitable pump.

Between the body 17 and the upper and lower ends of the stationary jacket 18 there are sealing assemblies 20 and 21, the latter of which is 50 supported on the external, annular shoulder 22 of the rotatable body 17 and the former of which is maintained in place by the retaining nuts 23 screwed onto the upper end of the body 17. The swivel may be supported by a suitable bail 24.

55 The upper end of the sample recovery tube 6

extends up through the swivel and fits closely through the body 17.

The body 17 of the swivel has an inside annular channel 25 therearound which is enclosed by the tube 6 thus forming a chamber and the body 17 has an inlet port 26 through which the drilling fluid may enter said chamber. This drilling fluid flows from the chamber downwardly through one or more ducts 27 and on down through the channel 7 and out through the duct 5 to the formation being drilled. This drilling fluid is under pressure and will be returned up around the drill stem and out through the flow line 13 or up through the sample recovery tube 6 depending upon whether the valve 14 is opened or closed. The valve 14 may be partly opened so that part of the drilling fluid will be returned up around the drill stem and out through the flow line 13 and partly up through the tube 6. This return flow of the drilling fluid is under the complete control of the operator through the instrumentality of the valve 14.

During ordinary drilling operations where sample recovery is not desired the valve 14 may be completely opened and in such event the major portion of the drilling fluid will be returned up around the drill stem and carried off through the flow line 13. However, should a recovery of a sample be desired the valve 14 may be entirely or partly closed so that a sufficient portion of the drilling fluid will be caused to return up through the sample recovery tube to float out the desired samples through said tube to the ground surface for inspection. The drilling fluid with the samples therein may be recovered from the upper end of the tube 6 in any preferred manner.

It is to be understood that the drilling will be carried on by the rotary process. The drill stem may be rotated by any suitable type of rotary drilling equipment connected thereto above the casing head.

What I claim is:

1. Apparatus for drilling bore holes comprising, a casing set in the bore, a rotatable tubular drill stem extending into the bore through the casing and spaced therefrom to provide a return channel, a seal between the upper end of the casing and the stem, an outflow pipe leading from said channel beneath the seal, a valve controlling said outflow pipe, a core forming drill on the lower end of the stem having a core receiving inlet and an

inside, upwardly facing, shoulder, a sample return tube within and spaced from the stem to form a supply channel for drilling fluid around the tube, said tube being supported on the shoulder of the drill, said drill having a duct leading downwardly therethrough from the supply channel through which drilling fluid may be supplied to the formation being drilled, means for supplying a drilling fluid under pressure to said supply channel, said valve forming means for controlling the flow of said fluid through the return channel whereby the velocity of the fluid returning through said tube may be varied.

2. Apparatus of the character described comprising a tubular rotatable drill stem, a swivel connected to the upper end of the stem and comprising, a tubular swivel body having an inlet port and an inside annular channel connected with said port, a stationary jacket around the body and sealed therewith above and beneath said port, an inlet through the jacket for the inlet of drilling fluid into said channel, said body having upper ducts leading downwardly from the channel into the stem, an annular drill on the lower end of the stem having a central core inlet and having a duct leading downwardly through the drill, a sample receiving tube supported on the drill and aligned with the core inlet and spaced inwardly from the duct through the drill and thus forming a channel for drilling fluid between the stem and tube, which channel communicates with said upper and lower ducts, said apparatus having a return channel outside of the stem and means for controlling the flow of the returning fluid through the return channel whereby the return of fluid through the tube may be controlled.
